(57) **CLAIM**

I claim the ornamental design for display screen or portion thereof with virtual multiple sided graphical user interface icon queue, as shown and described.

DESCRIPTION

The file of this patent contains at least one drawing executed in color. Copies of this patent and color drawings will be provided by the United States Patent and Trademark Office upon request and payment of the necessary fee. The color shown on the claimed design forms no part thereof.

The FIGURE is a front view of a display screen or portion thereof with virtual multiple sided graphical user interface icon queue.
